(57) **CLAIM**

The ornamental design for an indoor wall with built-in home appliances, as shown and described.

DESCRIPTION

FIG. 1 is a front perspective view of the indoor wall with built-in home appliances showing our new design;

FIG. 2 is a front view thereof;

FIG. 3 is a rear view thereof;

FIG. 4 is a left view thereof where the right view is a mirror image;

FIG. 5 is a top view thereof;

FIG. 6 is a bottom view thereof;

FIG. 7 is a reference view showing the use state that the widgets are displayed on the front middle right cover of the claimed design;

FIG. 8 is a reference view showing the state of use that the front cover is being raised;

FIG. 9 is a front perspective view in a condition that the front cover has been raised;

FIG. 10 is a front view of FIG. 9;

FIG. 11 is a rear view of FIG. 9;

FIG. 12 is a left side view of FIG. 9 where the right side view is a mirror image;

FIG. 13 is a top view of FIG. 9;

FIG. 14 is a bottom view of FIG. 9; and,

FIG. 15 is a reference view showing the use state that the front center part of the claimed design can be used as a TV.
